United States Patent Office

Des. 190,560
Patented June 13, 1961

190,560

CASTER

Robert E. Sheahan, Woodbridge, Conn., assignor to The Bassick Company, Bridgeport, Conn., a corporation of Connecticut

Filed Sept. 21, 1959, Ser. No. 57,629

Term of patent 14 years

(Cl. D10—6)

FIG. 1.

FIG. 2.

FIG. 3

FIG. 1 is a side elevational view of a caster, showing my new design;

FIG. 2 is an end elevational view as seen from the right of FIG. 1; and

FIG. 3 is a top plan view thereof.

The essential features of the design reside in the solid line portions.

I claim:

The ornamental design for a caster, substantially as shown and described.
